Arden Foulger
ATTORNEY

UNITED STATES PATENT OFFICE.

THOMAS RAYMOND ARDEN, OF BELLMORE, NEW YORK, ASSIGNOR TO JULIUS CHEIN, OF NEW YORK, N. Y.; ELIZABETH H. CHEIN EXECUTRIX OF SAID JULIUS CHEIN, DECEASED.

AEROPLANE TOY.

Application filed July 30, 1924. Serial No. 729,058.

My invention relates to improvements in toys.

In the manufacture of toys intended to be sold at a low price it is important that 5 the number of operations and the attendant labor cost be kept at a minimum.

An object of my invention is to provide a novel, attractive and useful toy. Another object of my invention is to produce a toy 10 of low cost. Another object of my invention is to provide a toy having a minimum number of parts. Another object of my invention is to produce a toy in which the parts when assembled may be secured together in a firm and novel manner and without the use of solder or the like.

I accomplished these objects by the device illustrated in the accompanying drawings in which

20 Figure 1 is a side view of my improved toy in the form of mechanical toy aeroplane.

Figure 2 is a detail of the driving mechanism and

25 Figure 3 is a view of the blank.

Similar characters of reference refer to similar parts throughout the several views.

The body of my improved toy is preferably formed from an integral blank 1. This 30 blank is preferably cut or stamped from sheet iron and includes a wing section 2, a chassis case section 3, a tail section 4, and rudder section 5, so arranged that the blank may be folded or stamped in a single operation 35 by means of a die, to serve as the frame or body of the toy.

The forward or chassis section 3 of the blank is folded or bent over so that the central portion 6, adapted to carry the propeller 40 is positioned at a right angle to the plane of the wing section 2 and the two side portions 7 and 8 respectively are bent over at right angles to the central portion. The members 11 and 12 are cut from and depressed in the wings 2 to serve as locking means. The lugs 7' and 8' respectively of the sides 7 and 8 are placed under apertures 9 and 10 respectively in the wings 2 and are bent over outwardly on the under side of the wings between members 11 45 and 12 and the wings 2 to bind the lugs in

their seats against the wings and to prevent their displacement.

A shaft 13 carrying a spring motor 14 may then be seated in the chassis section 55 3. I prefer for this purpose to provide an aperture or seat 15 in one side of the chassis case 3 to receive an end of the shaft 13 and an open seat 16 in the opposite side of the case 3 to carry the shaft 13 at the 60 other end of the motor 14.

A shaft 13 carrying the motor 14 is inserted in the seats 15 and 16 and a lip 17 adjacent the seat 16 is then pinched over across the open mouth 16' of the seat 16 65 thereby closing the mouth and holding the shaft therein.

The spring motor 14 is preferably provided with a key 18 by which the spring may be wound and with a ratchet 19 to 70 hold the spring. I preferably provide on the side of the chassis case one or more projections or teeth 20 which are preferably bent over slightly to engage the ratchet 19 of the spring motor to hold the spring as 75 it is wound. Shafts 21, 22 may be provided in the case 3 to carry the gears and pinions by which the power from the spring motor 14 is transmitted in the usual manner to the shaft 22 carrying the traction 80 wheels 25.

A tail support 26 may be stamped out of the tail section 4. A section 3' extending from the tail section 4 to the front of the toy may be rounded to represent the 85 body of an aeroplane and a section 28 may be cut out to represent the cock pit. A propeller 29 may be mounted on the front of the toy. In the device as I have shown it this propeller is idle.

I preferably provide a plurality of ribs laterally of the wing and tail sections and a rounded marginal edge 32 for the purpose of strengthening the device. The toy may be decorated in any desired manner.

Having thus described my invention what I claim is:

In a toy aeroplane having a fuselage, wings and a tail section formed integrally therewith, a tail support bent from said tail section, a chassis section formed integrally with said fuselage, parallel side members

on said chassis and lugs on said side members, ribs cut and depressed in said wing members engaging said lugs to lock said chassis to said wing section, diametrically disposed seats in said parallel side members, motor means mounted in said seats and a retaining member formed integrally with said side member to lock the motor means

in said seats, a ratchet on said motor means and a projection formed integrally with one of said side members and in engagement with the teeth of said ratchet.

In testimony whereof, I have signed my name to this specification, this 24 day of June, 1924.

THOMAS RAYMOND ARDEN.
